ROOF DRAINAGE SYSTEM FOR TOLL
BOOTH CANOPIES

Benjamin Cooper, New York, and Murray J. Charet, Brooklyn, N. Y.; said Charet assignor to said Cooper

Application August 4, 1950, Serial No. 177,636

5 Claims. (Cl. 108—1)

1

This invention relates to roof drainage systems and is particularly directed to drainage systems for use in connection with canopies for highway toll collection booths.

It is usual in highway toll collection stations to provide a canopy over the toll collection booth structures for the primary purpose of keeping snow and rain away from the area around the booths.

It is one object of this invention to provide a roof drainage system of the character described that is simple and functional.

It is another object of this invention to provide a roof drainage system of the character described in which the water drainage gutters are concealed from above so that they are less subject to erosion due to direct exposure to the elements, as in the case of ordinary drainage gutters.

It is another object of this invention to provide a roof drainage system of the character described wherein any water on the canopy roof flows into one or more drainage pipes conveniently located to pass into the toll booths for connection into the water disposal systems.

Other objects of this invention will in part be obvious and in part hereinbelow pointed out.

The invention accordingly consists in the features of construction, combination of elements and arrangement of parts which will be exemplified in the construction hereinbelow described and of which the scope of application will be indicated in the appended claims.

In the accompanying drawings, in which are shown two of the various possible illustrative embodiments of this invention:

Fig. 1 is a perspective view showing a canopy embodying the invention interconnecting three toll booths in a multi-lane toll collection installation,

Fig. 2 is a plan view of the canopy installation shown in Fig. 1,

Fig. 3 is a front elevational view of the canopy installation shown in Fig. 1,

Fig. 4 is a partial cross-sectional view taken on line 4—4 of Fig. 2,

Fig. 5 is a partial cross-sectional view taken on line 5—5 of Fig. 2,

Fig. 6 is a cross-sectional view taken on line 6—6 of Fig. 2,

Fig. 7 is a cross-sectional view taken on line 7—7 of Fig. 2,

Fig. 8 is a cross-sectional view taken on line 8—8 of Fig. 2, and

Fig. 9 is a view as in Fig. 5, but showing a modified construction.

2

Referring now in detail to the drawings, 10 represents a canopy structure for a three-booth toll collection installation embodying the present invention. Toll booths B are preferably of the type described and claimed in the co-pending patent application for Prefabricated Toll Collection Booths, Serial No. 175,132, filed July 21, 1950. The framework structure of the canopy shown is of the type described and claimed in the co-pending patent application titled Prefabricated Canopy for Toll Collection Booths, Serial No. 151,639, filed March 24, 1950.

Fixed to the ends of the toll booths are the usual fare indication signal lights C, employed to indicate to a customer or observer that a given toll transaction fare has been registered. There is also shown the usual treadles, T, for counting the passage of vehicles through the toll collection lanes, and a maintenance building M, which may house toll recording equipment and heat and light supply facilities for the collection booths.

The roof drainage systems embodied in this invention are supported on the canopy framework comprising a plurality of hollow lateral girder members 11, two for each toll booth and one at the open end of the canopy, made of sheet metal and approximately square in cross-section. (Figs. 2, 3, 4, 6 and 7.) Bolted against the ends of said lateral girder members are hollow transverse girder members 12 approximately rectangular in cross-section.

Lateral girder members 11 adjacent the toll booths may be secured thereto as by angle irons 13, one arm of which is welded to said girder members and the other arm of which is bolted as by bolts 14 to the top of the toll booth (Fig. 4).

Centrally located between transverse girder members 12 and fixed against the top of lateral girder member 11, as by bolts 15, is a transverse channel iron member 16 (Figs. 2 and 4).

The canopy roof comprises corrugated sheet metal 17 mounted on transverse girder members 12 as by bolts 18, and centrally supported on the top of channel iron member 16 as by bolts 19 (Fig. 5). In the embodiment shown in Fig. 5 the corrugated roof is slightly downwardly inclined from front to back, as indicated by the arrow, so that water will flow along the grooves of the corrugated roof 17 into the drainage system at the rear end of the canopy as hereinbelow described.

Transverse girder members 12 are surmounted by flashing members 20 having upwardly and downwardly extending ends and fixed to said girder members as by self-tapping screws 21.

There is further provided, at the upper outer

side of said girder members, trim piece 22, curled over the upwardly extending end of flashing member 20 and fixed against the girder member as by self-tapping screws 23 (Figs. 5, 8 and 9).

Outer lateral girder member 11 has welded against its top and flush with its outside face an angle iron 24 to which is fixed, as by self-tapping screw 26, trim piece 25, similar to said trim piece 22 (Figs. 4 and 7). There is welded against and along the inner side of angle iron 24 a plurality of U-shaped gutter brackets 27 adapted to support the drainage gutter 28. Said gutter is restrained against upward displacement by off-set flashing piece 29 fixed to trim piece 25 as by self-tapping screws 30. The upper end of trim piece 25 is curled over the upper end of said flashing piece. The outer end of transverse channel iron member 16 has welded to it a short piece of angle iron 31, the top surface of one arm of said angle iron being flush with the top surface of said channel iron member for the purpose of supporting the outer end of sheet metal roofing 17. It should be noted that angle iron 31 and sheet metal roofing 17 overhang the top of gutter 28 so that water will drip into said gutter rather than seep below into the canopy structure.

The inner end of transverse channel iron member 16 has welded to it a short piece of angle iron 32, similar to angle iron 31, the top surface of one arm of said angle iron being substantially flush with the top surface of said channel iron member. Welded against angle iron 32 is a gutter bracket 33 adapted to support the drainage gutter 34. Said gutter communicates with and is further supported by the inner ends of front and rear drainage gutters 39 and 41, hereinbelow detailed. Likewise, gutter 28, hereinabove detailed, communicates with the outer ends of said front and rear drainage gutters (Figs. 4 and 5).

There is provided a recess in the wall of the maintenance building in which is fixed a channel iron 36 to which the inner ends of the transverse girder members 12 are fixed. Said channel iron is provided with flashing members 35 and 37, the purpose of which is to keep water confined to the top of the canopy roof where it may properly drain off. It should be noted that one end of flashing member 35 overhangs into gutter 34 so that water will drip into the gutter, rather than seep below and under the canopy.

Welded against the inner sides of the front transverse girder member 12 are a plurality of drainage gutter brackets 38 adapted to support U-shaped drainage gutter 39. It should be noted that the downwardly extending end of flashing member 20 extends into said gutter so as to prevent water from leaking down between girder member 12 and the gutter (Figs. 5 and 8).

Welded against the inner sides of the rear transverse girder member 12 are a plurality of drainage gutter brackets 40 adapted to support U-shaped drainage gutter 41. Here again it should be noted that the downwardly extending end of flashing member 20 extends into said gutter.

Communicating with drainage gutter 41 at points opposite the ends of the toll booths are drain pipes 42, one for each booth, extending into flexible couplings 43 and thence into conduits 44 extending into the toll booths for connection to the water disposal system.

It will now be evident from an inspection of Fig. 5 that, by virtue of the downward inclination of the roof towards the rear of the canopy, most of the water will be carried to the rear of

the canopy to be drained off from gutter 41 into the drain pipes 42. Thus water will flow along the grooves of the corrugated roof, against the flashing member 20 and back through the end openings of the corrugated sheet metal 17 into gutter 41.

The brackets 38 are positioned so that gutter 39 is inclined slightly downwardly at the open end of the canopy, thereby compelling water in gutter 10 39 to flow down and around the outer end of the canopy into gutter 41. Likewise, brackets 40 are positioned to pitch gutter 41 so as to drain into one of the drainage pipes 42.

In the modification shown in Fig. 9, the corrugated sheet metal roof 17 is slightly bent in the center where it is fixed to transverse channel iron member 16, so that it inclines downwardly from the center toward the front and rear of the canopy as shown by the arrows. This modification provides for roof drainage at both the front and the rear of the canopy. To this end the front gutter 46, supported by brackets 45, is provided at each booth with drain pipes 47, flexible couplings 48 and conduits 49 similar to those above mentioned 25 at the rear of the canopy. Here again the gutters are preferably pitched to drain into one of the pipes 41 so that standing water cannot remain in the gutters. The operation of the modified system is, of course, similar to that above described for drainage at the rear end of the canopy only. The use of the modified system is preferable in areas subject to heavy downfalls of rain.

It will thus be seen that there is provided a 35 roof drainage structure in which the several objects of this invention are achieved and which is well adapted to meet the conditions of practical application.

As various possible embodiments might be made of the above invention, and as various changes might be made of the embodiment set forth, it is to be understood that all matters herein set forth or shown in the accompanying drawings are to be interpreted as illustrative and not in a limiting sense.

Having thus described our invention, we claim as new and desire to secure by Letters Patent:

1. In combination, corrugated roof decking comprising alternate parallel crest and channel portions, said decking being inclined lengthwise of said portions, a flashing member at the lower end of said decking running longitudinally of said lower end and partially projecting beneath said end in contact with the channel portions, and a drain gutter disposed beneath said decking, said flashing extending to said drain gutter whereby water running down the channels of the decking onto the flashing, will run beneath the crest portions of the decking from the flashing to the drain gutter.

2. A concealed roof drainage system for a corrugated roof comprising corrugated decking disposed on an inclined plane lengthwise of the corrugations, a flashing member having a portion upwardly extending in horizontally spaced parallel relation with the lowermost end of said decking, said flashing extending beneath said end of said decking, a drainage gutter disposed under said decking, and a downwardly extending portion of said flashing member projecting down into said gutter whereby said flashing member receives water from the exposed groove-forming corrugations and diverts said water under the open-ended adjacent corrugations into said drainage gutter.

3. A concealed roof drainage system for a corrugated roof comprising, corrugated decking disposed on an inclined plane lengthwise of the corrugations, a flashing member having a portion upwardly extending in horizontally spaced parallel relation with the lowermost end of said decking, said flashing extending beneath said end of said decking, a drainage gutter disposed under said decking, and a downwardly extending portion of said flashing member projecting down into said gutter whereby said flashing member receives water from the exposed groove-forming corrugations and diverts said water under the open-ended adjacent corrugations into said gutter, and conduit means communicating with said gutter to withdraw water therefrom.

4. In combination, corrugated roof decking comprising alternate parallel crest and channel portions, said decking being inclined lengthwise of said portions, flashing means at the lower end of said decking running longitudinally of said lower end and partially projecting beneath said end in contact with the channel portions, and a drain gutter disposed beneath said decking, said flashing means extending to and communicating with said drain gutter whereby water runs down the channels of the decking onto the flashing, and means to divert the water beneath the crest portions of the decking to the drain gutter.

5. A concealed roof drainage system for a corrugated roof comprising corrugated decking disposed on an inclined plane lengthwise of the corrugations, flashing means having means upwardly extending in horizontally spaced parallel relation with the lowermost end of said decking, said flashing means extending beneath said end of said decking, a drainage gutter disposed under said decking, and means downwardly extending from said flashing means communicating with said gutter whereby said flashing means receives water from the exposed groove-forming corrugations and diverts said water under the open-ended adjacent corrugations on to said communicating means and into said gutter.

BENJAMIN COOPER.
